United States Patent Office

Des. 210,370

Patented Mar. 5, 1968

210,370

VITAMIN TABLET OR SIMILAR ARTICLE

Luther H. Kroninger, Jr., and Dean R. Straka, Evansville, Ind., assignors to Mead Johnson & Company, a corporation of Indiana

Filed Mar. 8, 1967, Ser. No. 6,135

Term of patent 14 years

(Cl. D16—3)

FIG. 1 is a side elevation of a vitamin tablet or similar article showing our new design, the opposite side is a mirror image of the side shown;

FIG. 2 is a front elevation thereof;

FIG. 3 is a rear elevation thereof;

FIG. 4 is a top plan view thereof; and

FIG. 5 is a bottom plan view thereof.

We claim:

The ornamental design for a vitamin tablet or similar article, as shown and described.
